UNITED STATES PATENT OFFICE.

WILLIAM S. BURNETT, OF MILWAUKEE, WISCONSIN, ASSIGNOR TO MORSE CODE SIGNAL CO., OF MILWAUKEE, WISCONSIN, A CORPORATION OF WISCONSIN.

ELECTROMAGNETIC SELECTIVE DEVICE.

1,119,681.

Specification of Letters Patent.

Patented Dec. 1, 1914.

Application filed August 23, 1909. Serial No. 514,131.

To all whom it may concern:

Be it known that I, WILLIAM S. BURNETT, a citizen of the United States, residing at Milwaukee, county of Milwaukee, and State 5 of Wisconsin, have invented new and useful Improvements in Electromagnetic Selective Devices, of which the following is a specification.

My invention relates to improvements in 10 electro-magnetic selective devices.

The object of my invention is to provide means for operating controlling mechanisms at any one of a series of stations along a single line of electrical conduction 15 to the exclusion of the other, said controlling mechanism being employed for any desired purpose, such for example, as the operation of signal unlocking or locking mechanism.

20 In the following description, reference is had to the accompanying drawings, in which—

Figure 1 is a side elevation of the apparatus used at a local or controlled station. 25 Fig. 2 is a rear elevation of the same, showing the parts as they appear at an unselected station during a signal unlocking operation at a selected station. Fig. 3 is a detail view of a detached portion of the 30 mechanism shown in Fig. 2, showing the parts in normal position. Fig. 4 is a similar view, showing the parts in station selecting position, preparatory to the unlocking operation. Fig. 5 is a detail side view 35 of the selecting magnet, armatures with their supporting connections, signaling apparatus, and the selecting wheel and its pawl and ratchet actuator. Fig. 6 is a plan view of the same, showing also the selecting 40 magnets. Fig. 7 is a detail rear view of the unlocking shoe, showing the guard finger in cross section. Fig. 8 is a front view of the same. Fig. 9 is a diagrammatic view of a series of instruments connected at 45 different stations with a single line of conduction and Fig. 10 is a sectional view on line *a—a* of Fig. 5.

Like parts are identified by the same reference characters throughout the several 50 views.

The general features of the apparatus described and claimed herein are shown and described, but not claimed, in my former application filed April 12, 1909, Serial No. 55 489,319, in which application, however,

electro-magnets of different structure are disclosed from those illustrated in connection with this application and the working parts of the apparatus herein illustrated are somewhat different in structure, although operating on the same general principle as the parts disclosed in said previous application.

In the drawings of this application, an ordinary electro-magnet 1, having two sets 60 of coils, as shown, is employed as a selecting magnet. This magnet is provided with two vibrating armatures 3 and 5 respectively, the armature 3 being centrally pivoted upon a supporting rod 7, which is 65 mounted in suitable frame bearings at 8 and 9. The armature 5 is rigidly connected with the rod 7 and a bell clapper arm 11 is rigidly connected to the armature 5 and provided with a clapper weight 13, whereby a 70 vibration of armature 5 will cause the bell to sound.

The armature 3 is employed to actuate a selecting wheel 15 through an arm 17 rigidly connected with a hub 18 on said armature and through the pawls 19, ratchet member 20 and shaft 21. The ratchet member 20 and selecting wheel 15 are both rigidly connected with the shaft 21. An alternating current being employed, its reversal 80 in polarity causes the armature 3 to vibrate. This vibratory movement is utilized to actuate the ratchet 20 and the selecting wheel 15 which will be more clear from an inspection of Fig. 5. The selecting wheel is 85 provided with one or more notches 22, which, when the wheel is in selective position, will permit of an unlocking operation for releasing the bell clapper arm 11 as herein-after described.

A resilient locking arm 27 is provided with a projection 29 adapted to normally engage an arm 30, which is rigidly connected with the rod 7, thereby preventing the rod 7 and armature 5 from vibrating and 100 thus locking the arm 11 and bell clapper 13 against signaling movement. The resilient arm 27 is provided with a segmentally curved lip 33. This lip 33 is provided with an angularly disposed hook shaped end portion, the shank 34 of which is bent rearwardly, forming an angularly disposed shoe at 35, with the extremity 36 extending upwardly and forwardly in the rear of the lip, as best shown in Fig. 7. A guard finger 38, 110

extends downwardly beyond the hook and then rearwardly and upwardly as best shown in Figs. 1 and 2.

A bell unlocking electro-magnet at 40 has 5 pole pieces 41 extended, and an armature 42 is pivoted at 43 between the pole pieces, one end of the armature being heavier than the other, whereby it normally assumes an angular position, as shown in Fig. 3, but 10 may be swung to a horizontal position by the magnetic pull of said pole pieces, when the magnet is energized. The reversals of the magnetism through the pole pieces 41 do not cause a vibration of armature 42 as 15 any sufficient magnetization will cause the armature to align itself with the pole pieces, the interval of time, if there be any, between the pulsations used for setting purposes not being long enough to permit retraction of 20 this armature between pulsations or impulses. This armature carries an arm 45, which extends radially from its pivotal axis and is provided with a projection 47 adapted to enter the notch 22 in the selecting wheel 25 15, or to bear upon the periphery and limit the swinging movement of the armature when not in registry with the notch. Another arm 50 is also axially connected with the armature and carries a stop 51, which, 30 when the armature is actuated by the magnet 40, moves to a position in the path of one or more arms 53, which extend radially from the ratchet actuated rod 21, whereby the rotary movement of this rod and selecting 35 wheel 15 is limited whenever the magnet 40 is energized. The arm 50 carries a finger 55, preferably mounted upon a branch 56 of the arm, and hinged thereto in such a manner as to allow a limited horizontally 40 swinging movement, the finger being swung in a vertical plane by the arm 50 and in an arc having the armature axis as a center. When so swung the finger travels along the rear surface of the lip 33 into and out of 45 proximity to the shoe 35, and when the projection 47 enters a notch 22 in the selecting wheel, the right hand or heavier end of the armature swings downwardly to such an extent as to carry the finger 55 over the shoe 50 35 to a point between it and the guard finger 38, as shown in Fig. 4, the finger contacting with and pushing the shoe forwardly, (inwardly toward the magnet) in passing to such position. As soon as the finger passes 55 the shoe, the latter springs rearwardly across the path of the finger so that the finger will engage the front surface of the shoe during its next upward movement. When the magnet 40 is again energized, it swings finger 60 55 upwardly, and it then engages the front surface of the shoe 35 and passes in front of the shoe and along the hook extremity 36 and front surface of the lip 33, crowding the latter rearwardly or to the left of its position in Fig. 1 to a sufficient extent to disen-

gage the latch projection 29 from the arm 30, thus unlocking the bell clapper and permitting an oscillation of armature 5, rod 7, and clapper rod 11. The bell will then continue to sound while the alternating current is maintained. When the magnet 40 is again deenergized, by interrupting the circuit or by a cessation in current production, the gravity tilting movement of the armature 42 will swing finger 55 downwardly. But during the bell clapper releasing movement, it moved past and above the hook extremity 36 pushing the latter rearwardly in passing. The part 36, by its resilient reaction, then extends across the path of finger 55, and as this finger moves downwardly it is guided through the opening to normal position in the rear of shoe 35, as shown in Fig. 3. This leaves the arm 27 again free to swing forwardly to normal locking position with projection 27 in engagement with arm 30, as shown in Fig. 1. It will therefore be understood that the extreme tilting movement of the armature 42 at a selected station causes finger 55 to first force its way downwardly across the rear face of the angularly disposed shoe and then pass upwardly in front of it to push the lip backwardly and release the bell when the current is resumed. Also that during the upward clapper releasing movement, the finger forces its way past the hook extremity 36, the function of which is to guide the finger 55 through to the rear side of the shoe when the current again ceases.

In Fig. 9, I have illustrated a series of stations B, C, D, connected in series with one central station provided with apparatus, such as an alternating current generator or magneto A for producing and reversing the current. Each of the stations is provided with a selecting wheel 15, the various selecting wheels 15 at the different stations being provided at different angular positions with notches 22 corresponding respectively to the 100 different stations.

To operate the selecting wheels at the various stations, a current will be set up in the conductor. Armature 3 will then be vibrated to actuate the selective wheel 15 at each station, until the wheel at the desired station reaches a position where projection 47 may register with and enter the notch 22 in such wheel. If the current then ceases, armature 42 will tilt by gravity, and as the projection 47 then enters notch 22 in the selecting wheel at the station to be called, the finger 55 at that station will move past the margin of shoe 35 and assume a position below and a little to the front of the shoe margin, as shown in Fig. 4. The current being then restored, armature 42 will be swung by magnet 40 to carry finger 55 along the front face of the shoe and hook extremity 36 to the front face of the lip 33,

crowding the latter to the rear and unlocking the bell clapper by withdrawing projection 29 from arm 30, after which, armature 5 is permitted to vibrate and sound the bell.

5 In the meantime, all the ratchet actuators will be in operation to cause the selecting wheels to step around to a position where the stops 51 will engage arms 53, thus establishing a zero point from which all the 10 selecting wheels will start in a subsequent operation.

When the current again ceases to flow through the line, the armature 42 at the selected station will again move to tilted position, carrying the finger 55 through the gap between hook extremity 36 and lip 33 to normal position in the rear of shoe 35. The selecting wheel having moved to zero position, the projection 47 cannot enter the 20 notch therein, and the finger 55 will therefore not move over the margin of the shoe as it did when the station was selected. At all the other stations, the movement of their armatures 42 will merely cause the fingers 25 55 to vibrate in the rear of the shoe and lip 33 since the down tilting movement of the armatures is not sufficient to carry these fingers over the margin of the shoe.

While I have shown and described the 30 rocking armature as used to operate the unlocking mechanism of a bell sounder, it will be understood that this armature movement may be utilized to perform any desired operation, such for example, as closing an 35 electrical switch controlling local electrical mechanism, either in addition to the unlocking operation above described or independently thereof. Such a switch is illustrated at 60 in Fig. 9, as used for controlling 40 circuit of a local battery 61, which may thus be operated for any desired purpose.

Having thus described my invention, what I claim as new, and desire to secure by Letters Patent, is—

45 1. In apparatus of the described class, the combination of a series of stations, each having an electromagnet provided with a set of vibratory armatures, means for normally locking one of said armatures against vibration, a swinging armature loaded at one end to swing downwardly by gravity, an electro-magnet adapted, when energized, to lift the loaded end of said armature, unlocking mechanism operatively connected therewith, 50 and a selecting member actuated from the free armature of the first named magnet and controlling the unlocking operations of the swinging armature by limiting the movement of the latter at all points but one in 55 the field of movement of the selecting member.

60 2. In apparatus of the described class, the combination of a series of stations each having an electro-magnet provided with a set 65 of vibratory armatures, means for normally

locking one of said armatures against vibration, an electro-magnet provided with a swinging armature, and unlocking mechanism operatively connected therewith, a selecting member actuated from the free 70 armature of the first mentioned magnet and controlling the unlocking operations of the swinging armature.

3. In apparatus of the described class, the combination of a series of stations each having an electro-magnet provided with a set of vibratory armatures, means for normally locking one of said armatures against vibration, an electromagnet provided with a swinging armature, and unlocking mechanism operatively connected therewith, a selecting member actuated from the free 75 armature of the first mentioned magnet and controlling the unlocking operations of the swinging armature, the selecting members 80 at the different stations being characteristically different and adapted to permit the unlocking operations of the swinging armatures at different intervals at the several stations. 90

4. In apparatus of the described class, the combination of a series of electrically connected stations, a pair of electrically operated vibratory armatures at each station, electro-magnetic means for vibrating the 95 same, means for locking one of the armatures against vibration, electro-magnetic mechanism for unlocking said armature, a selecting member at each station characteristically different from those of the other stations, 100 said selecting member controlling the unlocking mechanism, and a device connected with the unlocking mechanism, for arresting the operations of each selecting member at a common zero point, the selecting characteristic in each member being at a different 105 distance from its zero point from that of any other member.

5. In apparatus of the described class, the combination of a series of electrically connected stations, a pair of electrically operated vibratory armatures at each station, electro-magnetic means for vibrating the same, means for locking one of the armatures against vibration, electro-magnetic 110 mechanism for unlocking said armature, a selecting member at each station characteristically different from those of the other stations, said selecting member controlling the unlocking mechanism, and a device connected with the unlocking mechanism, for arresting the operations of each selecting member at a common zero point unequally distant, in each member, from the selecting 115 characteristic, said unlocking mechanism, 120 comprising a swinging armature, an unlocking finger connected therewith, and a movable member operatively connected with the lock and provided with a shoe angularly disposed with reference to the plane 125 130

of movement of the unlocking finger, the selecting member, when in selecting position, being adapted to permit said finger to move over the margin of said shoe to a position for engagement with its opposite side and said finger, when, in such engagement, being adapted to actuate the movable member to unlocking position.

6. In apparatus of the described class, the combination of an electro-magnet, a vibratory armature therefor, a movable member provided with means for locking said armature, when in one position of adjustment, a shoe angularly disposed with reference to the plane of movement of the unlocking member connected with said member, a reciprocating finger adapted to normally swing along one side of said shoe and unlocking member, a rotary selector adapted to normally limit the movement of said finger and provided with a notch adapted in one position to permit the finger to move over the margin of said shoe to a position for engagement with its opposite side, a guard arm for said finger whereby said finger when in such engagement is adapted to move in one direction to actuate said member to unlocking position, and in the other direction to pass between said member and shoe to normal position, electro-magnetic means for actuating the selector and electro-magnetic means for actuating said finger.

7. In apparatus of the described class, the combination of an electro-magnet, a vibratory armature therefor, a movable member provided with means for locking said armature, when in one position of adjustment, a shoe angularly disposed with reference to the plane of movement of the unlocking member connected with said member, a reciprocating finger adapted to normally swing along one side of said shoe and unlocking member, a rotary selector adapted to normally limit the movement of said finger and provided with a notch adapted in one position to permit the finger to move over the margin of said shoe to a position for engagement with its opposite side, a guard arm for said finger whereby said finger when in such engagement is adapted to move in one direction to actuate said member to unlocking position, and in the other direction to pass between said member and shoe to normal position, together with electro-magnetic means for actuating the selector, and electro-magnetic means for actuating the finger.

8. In apparatus of the described class, the combination of an electro-magnet, a vibratory armature therefor, a movable member provided with means for locking said armature, when in one position of adjustment, a shoe angularly disposed with reference to the plane of movement of the unlocking member connected with said mem-

ber, an electrically actuated reciprocating finger adapted to normally swing along one side of said shoe and unlocking member, an electrically actuated rotary selector adapted to normally limit the movement of said finger, and provided with a notch adapted in one position to permit the finger to move over the margin of said shoe to a position for engagement with its opposite side, a guard arm for said finger whereby said finger when in such engagement is adapted to move in one direction to actuate said member to unlocking position, and in the other direction to pass between said member and shoe to normal position, together with a stop connected with said finger, adapted, when the finger is in one position of adjustment, to limit the movement of the selector.

9. In apparatus of the described class, the combination of a series of stations, each having an electro-magnetic device provided with two vibratory armatures, a signal operating device under the control of one of said armatures, means for normally locking said armature against vibration, a rocking armature and movable mechanism in operative relation thereto, and a selector actuated from the other one of the armatures, and controlling the movable mechanism.

10. In apparatus of the described class, the combination of a series of stations, each having an electro-magnetic device provided with two vibratory armatures, a signal operating device under the control of one of said armatures, means for normally locking said armature against vibration, a rocking armature and movable mechanism in operative relation thereto, and a selector actuated from the other one of the armatures and controlling the movable mechanism, and means, controlled by the rocking armatures of all the stations for arresting the movement of the selectors at a common zero point.

11. The combination with an electro-magnetic step by step mechanism provided with armature actuating pole pieces and including an actuating armature, pivoted to swing alternately at its respective ends into and out of proximity to pole pieces of opposite polarity, of an oscillatory armature pivoted to swing at its respective ends simultaneously into and out of proximity to pole pieces of opposite polarity, means controlled by the step by step mechanism for determining the length of the stroke of said oscillatory armature, and a movable signal controlling member mechanically controlled by said oscillatory armature through variations in the character of its stroke.

12. The combination with an electro-magnetic step by step mechanism provided with armature actuating pole pieces and including an actuating armature, pivoted to

- swing alternately at its respective ends into and out of proximity to pole pieces of opposite polarity, of an oscillatory armature pivoted to swing at its respective ends simultaneously into and out of proximity to pole pieces of opposite polarity, means controlled by the step by step mechanism for determining the length of the stroke of said oscillatory armature, and a movable signal controlling member mechanically controlled by said oscillatory armature through variations in the character of its stroke, together with stopping and releasing devices for the step by step mechanism arranged to provide a zero point from which the step by step movements may originate.
13. The combination with a main line of conduction, of an electrically actuated armature responsive to alternating current impulses to produce motion in two directions, another armature responsive to produce motion in two directions, and a selector, actuated with each movement of the first mentioned armature to control the character of the strokes of the other armature.
14. The combination with a main line of conduction, of an electrically actuated armature responsive to alternating current impulses to produce motion in two directions, another armature responsive to produce motion in two directions, and a selector, actuated by the first mentioned armature to control the character of the strokes of the other armature, together with a signal control mechanism operative during strokes of one character performed by said last mentioned armature.
15. The combination with a main line of conduction, of a series of selectors along said line constituting stations, each selector being provided with an electrically actuated member selectively responsive to reversals in current polarity, another armature and means operated with each movement of the first mentioned armature for controlling the movements of the second.
16. The combination with a main line of conduction, of a series of selectors along said line constituting stations, each selector being provided with an electrically actuated member selectively responsive to reversals in current polarity, another armature, and means operated by the first mentioned armature for controlling the movements of the second, together with locking mechanism at each station controlled by the last mentioned armature.
17. A signaling system having a central station and substations united by a line circuit, a step-by-step signal receiving device having an operating winding provided at each substation, a step-by-step element and two armatures coöperating therewith controlled by said winding and having means to render same operatively selectively responsive to alternating impulses, and means at the central station to control the operations of said device.
18. A signaling system having a central station and substations united by a line circuit, a step-by-step signal receiving device having an operating winding provided at each substation, a condenser in series with each winding, a step-by-step element and two armatures coöperating therewith controlled by said winding and having means to render same operatively selectively responsive to alternating impulses, and means at the central station to control the operations of said device.
19. A signaling system having a central station and substations united by a line circuit, a step-by-step signal receiving device having an operating winding provided at each substation, a step-by-step element having means to render same operatively selectively responsive to alternating impulses, said means including an armature adapted to actuate said step-by-step element with each reversal of the current, and means at the central station to control the operations of said device.
20. A signaling system having a central station and substations united by a line circuit, a step-by-step signal receiving device having an operating winding provided at each substation, a condenser in series with each winding, a step-by-step element having means to render same operatively selectively responsive to alternating impulses, and means at the central station to control the operations of said device.
21. A system of the character described comprising a central station and substations united by a line circuit, the combination with a step-by-step element at each substation, means at the central station for transmitting positive and negative impulses, means to operate said step-by-step element selectively with each impulse to a selected position, and an electromagnetic device to operate said last aforesaid means.
22. A system of the character described comprising a central station and substations united by a line circuit, the combination with a step-by-step element at each substation, means at the central station for transmitting positive and negative impulses, and an escapement mechanism at each substation to control said step-by-step element and to operate the same one step with each impulse.
23. A system of the character described comprising a central station and substations united by a line circuit, the combination with a step-by-step element at each substation, means at the central station for transmitting positive and negative impulses, means to selectively operate said step-by-

step element in accordance with the polarity of the impressed impulse with each reversal of current, an electromagnetic device to operate said last aforesaid means, and a condenser in series with said electromagnetic device.

24. A system of the character described having a central station and substations united by a line circuit, a step-by-step element at each substation, step-by-step means to control same, means at the central station for impressing alternating currents on said circuit, an armature for operating said step-by-step element one step with each reversal of current, means to control a signal, an armature controlled by said step-by-step element to control said means, and a winding to control said armatures.

25. A system of the character described having a central station and substations united by a line circuit, a step-by-step element at each substation, step-by-step means to control same, means at the central station for impressing alternating currents on said circuit, an armature for operating said step-by-step element one step with each reversal of current, means to control a signal, an armature controlled by said step-by-step element, to control said last aforesaid means, a winding to control said armatures, and a plurality of magnetic circuits associated with said winding and said armatures.

26. In a system of the character described having a central station and substations united by a line circuit, a step-by-step element at each substation, step-by-step means to control same, means at the central station for sending positive and negative impulses over said circuit, an armature for operating said step-by-step element one step with each reversal of current, means to control a signal, an armature controlled by said step-by-step element to control said last aforesaid means, and a winding to control said armatures.

27. In a system of the character described having a central station and substations united by a line circuit, a step-by-step element at each substation, step-by-step means to control same, means at the central station for sending positive and negative impulses over said circuit, an armature for operating said step-by-step element with each reversal of current, a device to control a signal, an armature controlled by said step-by-step ele-

ment to control said device, a winding to control said armatures, and a plurality of magnetic circuits associated with said winding and said armatures.

28. In a system of the character described having a central station and substations united by a line circuit, a step-by-step element at each substation, step-by-step means to control same, means at the central station for sending positive and negative impulses over said circuit, an armature for operating said step-by-step element with each reversal of current, a device to control a signal, an armature controlled by said step-by-step element to control said device, a winding to control said armatures, a plurality of magnetic circuits associated with said winding and said armatures, the first aforesaid armature responding selectively to current of opposite polarity, and said last aforesaid armature responding irrespective of the polarity of current.

29. In a system of the character described having a central station and substations united by a line circuit, a step-by-step element at each substation, step-by-step means to control same, means at the central station for sending positive and negative impulses over said circuit, an armature for operating said step-by-step element with each reversal of current, means to control a signal, an armature controlled by said step-by-step element to control said last aforesaid means, a winding to control said armatures, a plurality of magnetic circuits associated with said winding and said armatures, the first aforesaid armature responding selectively to current of opposite polarity, and said last aforesaid armature responding irrespective of the polarity of the current.

30. In a system of the character described having a central station and substations united by a line circuit, a step-by-step element at each substation, means at the central station to transmit alternating current impulses, and electromagnetic means selectively responsive to said impulses to selectively set said element and to actuate the same with each reversal of current.

In testimony whereof I affix my signature in the presence of two witnesses.

WILLIAM S. BURNETT.
